UNITED STATES PATENT OFFICE.

MARQUIS F. SEELEY, OF FREMONT, NEBRASKA.

GRAIN-ELEVATOR.

SPECIFICATION forming part of Letters Patent No. 288,371, dated November 13, 1883.

Application filed December 26, 1882. (No model.)

To all whom it may concern:

Be it known that I, MARQUIS F. SEELEY, of Fremont, in the county of Dodge and State of Nebraska, have invented certain new and useful Improvements in Grain-Elevators; and I do hereby declare that the following is a full, clear, and exact description thereof, reference being had to the accompanying drawings, and to the letters of reference marked thereon, which form a part of this specification.

This invention relates to improvements in those structures for handling and storing grain, generally known as "grain-elevators." Its objects are to simplify the construction of such buildings and apparatus, to lessen their cost, and at the same time to increase the general efficiency of their operation.

It consists in the matters hereinafter described, and pointed out in the claims.

The structure shown as embodying my invention is more particularly adapted for use at a place where grain is received in wagons preparatory to being cleaned and shipped in cars or vessels; but its general features of construction are as well adapted for use in other places. It consists of a building, approximately square in plan, having a substantially unitary hopper-structure placed beneath it, which slopes from the sides of the building toward its center, and forms the bottom of a series of storage-bins extending to the roof, and of receiving-bins and a bin for cleaned grain placed under a working-floor in the central part of the building. All of the bins mentioned are constructed to discharge their contents at the lower ends of two elevator-belts extending to the top of the building. Each of these belts is arranged to discharge at its top into conveyer-spouts, which extend to all of the storage-bins, and to bins placed over a grain-cleaner and weighing-hopper. The said elevator-belts are so arranged, in connection with discharge-gates in the several bins, that the operations of cleaning the grain and elevating it to the storage-bins proceed simultaneously, and that the operation of handling the grain is facilitated in other ways, as will be herein-after more fully explained. Improvements in certain details of the operative parts and in the construction of the building are also embraced in my invention, and will be herein-after described.

Proceeding to describe my invention with reference to the accompanying drawings, Figure 1 is a plan view of a grain-elevator constructed as proposed by my invention. Fig. 2 is a vertical section of the same on line $x\ x$ of Fig. 1. Fig. 3 is a vertical section on line $y\ y$ of Fig. 1. Fig. 4 is a horizontal section on line $z\ z$ of Fig. 2. Fig. 5 is a detail section of the dumping devices over the receiving-bins. Fig. 6 is an enlarged view of the turn-spout and its connection with the top of the elevator.

A A are the outside walls of the building, and B B are two transverse partitions placed at equal distances from the sides of the building and extending to the roof. The two compartments adjacent to the outside walls formed by these partitions are divided into storage-bins C C by means of partitions c c c, which are arranged radially with reference to a point near the center of the partition-walls B, where the discharge-gates c' c' of said bins are placed. The bottoms C' C' of the bins C are inclined from the outside walls of the building toward the discharge-gates c' c', as shown more plainly in Fig. 2, so that all of the grain in the several bins may be discharged therefrom through the said gates upon an inclined surface, C², which conveys it to the lower ends of the two elevator-belts D D. The gates c' c' are placed in the walls of recesses c², formed in the partition-walls B, as shown in Figs. 1 and 3, and the handles by which such gates are opened and closed extend upward through a working-floor, E, and in a position convenient to the operator, stationed on said floor. The surface C² is placed between the partitions B B, and slopes from the walls of the building to a pit or depression, C³, below the level of the discharge-openings of the bins C, and at a little distance laterally therefrom.

The lower ends of the two elevator-belts D D are placed in the pit C³, and suitable guides, c⁴, are placed upon the surface C², to direct the grain falling upon the said surface from the bins C to the said belts. These elevator-belts are constructed in the customary manner, being inclosed in boxes or casings D' D', and passing over pulleys d d' at the bottom and top of the building, respectively.

The working-floor E is placed between the partitions B B, a short distance above the ground, and on a level with said floor. At one

side of the bins C is a driveway, F, which extends across the building, and is reached from the ground outside by suitably-inclined approaches, so that wagons loaded with grain 5 may be brought into the building. Beneath the driveway F are placed two receiving-bins, G, into which grain can be discharged through an aperture, f, in the floor of the driveway. The bins G have a common inclined bottom, G', which slopes to the pit C³, before mentioned, and they are separated by a central vertical partition, G². At the lower ends of the bins G are discharge-gates g, which are opposite the inlet-opening in the 10 elevator-box D', and operated by handles projecting upwardly through the working-floor F, by which the gates may be opened and grain admitted to the lower ends of the elevator.

20 Upon the upper portion of the incline C², below the floor E, is a bin, I, for cleaned grain, into which a grain-cleaner placed on the said working-floor is arranged to discharge. The front wall of the bin I is composed of two inclined partitions, I' I', which meet at an angle near the lower end of the incline C², and at the center thereof, as shown in Fig. 1. At the lowest point in said bin, adjacent to the point of intersection of the partitions I' I', two discharge-gates, i i, are placed in said partitions, 25 adapted to discharge the contents of the bin upon the lower portion of the surface C². From the point of intersection of the walls I' I', and between the gates i i, guide-partitions i' i' on 30 the inclined surface C² extend to the inlet-openings of the elevator-boxes, so that grain may be discharged from the bin I to either elevator by opening one or the other of the gates i.

35 By the arrangement of the incline C², bin I, and discharge-openings of the bins C, as described, it will be seen that grain may be delivered to the elevator-belts at either side from the storage-bins adjacent to that side, and to 40 either of the elevator-belts from the bin I for cleaned grain.

In order to secure economically a firm foundation for the storage-bins, and to obtain a sufficient capacity therein without unduly increasing the height of the building, the bottoms of said bins are placed near the ground, and the pit C³, into which said bins discharge, is sunk considerably below it. This mode of construction is also found desirable in order 50 to have the working-floor and floor of the driveway F (which latter is placed over the receiving-bins) as near the surface of the ground as possible.

In the space between the partition-walls B, 55 above the working-floor, are placed bins K, which are connected by means of spouts k with a grain-cleaner, L, placed on the working-floor over the bin I, and also bins M, which are provided with outlet-valves m, adapted to 60 discharge the contents thereof to a weighing-hopper, N, also located on the working-floor. The elevator-belts D D are arranged to dis-

charge at the top of the building into turn-spouts O O, each of which is adapted to be rotated by means of a vertical rod, O', extending to the working-floor, and provided with a handle, O², so as to connect with either one of a number of conveyer-spouts, P, which extend from each of the elevator-belts to all of the storage-bins C, and to the bins K over the 75 grain-cleaner, and to the bins M over the weighing-hopper.

The mode of operating the elevator arranged as described is as follows: Grain received from wagons or otherwise into one of the bins G, through the opening f in the floor of the driveway, is allowed to pass from said bin through the gate g to one of the elevator-belts, by which it is carried to the top of the building and delivered through one of the spouts P to the bin K, whence it passes through the spout k into the grain-cleaner, and then into the bin I. From this bin, by opening the proper gate, i, the grain is allowed to pass to the other elevator-belt, by which it is again carried to the top of the building and delivered into the storage-bins C. Instead of being placed in the storage-bins, as described, the cleaned grain may be delivered directly to the bin M over the weighing-hopper, preparatory 95 to its being weighed and delivered to the cars or vessel. The grain may be taken from either of the receiving-bins G while the other is being refilled by allowing the cleaned grain from the bin I to pass to either one of the elevators by one of the gates i i, as desired, and using the other elevator to draw from the receiving-bin which it is desired to empty. Grain is removed from either of the several storage-bins C by opening one of the gates c', 100 from which it will pass to the bottom of one of the elevator-belts, in the manner before described, and will be carried by such elevator-belts to the top of the building and deposited in the bin M over the weighing-hopper. Both 105 elevators may be used in raising grain from the storage-bins at the same time, one drawing from the bins on one side of the building and the other from those on the opposite side, and both elevators may draw in the same manner from the receiving-bins G G.

It will be apparent from the above description of the operation of the elevator that by the use of two elevator-belts and the arrangement of the bins and connecting-passages described the operation of cleaning the grain and elevating it to the storage-bins may proceed at the same time and by a continuous operation, whereby a great saving of time and cost is effected.

The pulleys d' d', over which the upper ends of the elevator-belts D D pass at the top of the building, are placed upon a shaft, d², which is provided with a pulley, d³, preferably placed between the belt-pulleys, and driven by a belt, 120 d⁴, from a pulley, d⁵, on a driving-shaft, d⁶. This shaft is located above the floor F and at right angles to the shaft d², and is connected to a steam-engine or other motor, preferably 125

placed upon an extension of the floor F, so that the said engine may be readily accessible by an operator stationed on said floor.

Upon the pulley-shaft d^2 , between the driving-pulley d^3 and the belt-pulleys d^4 , are placed two clutches, d^5 d^6 , which are operated in the ordinary manner to disconnect the said belt-pulleys from the driving-pulley d^3 . By the use of said clutches either of the belts D may be operated as desired, or both together.

It is found in practice that the elevator-structure is liable to settle unevenly on account of the weight of grain therein, and in order that such uneven settlement shall not affect the relative position of the several operative parts by which the elevator-belts are driven, I have placed the elevator-casings D^1 D^2 upon a foundation unconnected with the foundations of the main structure, and have attached the frames supporting the bearings of the said operative parts to said casings and made them independent of the frame of the building.

The bridge-trees D^2 D^3 , which support the bearings of the pulley-shaft d^2 , are attached to and supported upon the upper ends of the casings D^1 , and the bearings of the driving-shaft d^6 are supported on beams D^3 , also attached to the said casings, so that the shafts mentioned will remain in proper relative positions, notwithstanding any settlement that may occur in the main building. The frames D^4 , which support the ends of the conveyer-spouts P, are also supported upon the casings D, for the same reason.

The ends of the conveyer-spouts P terminate in a platform, P' , placed on the frame D^4 , and are arranged in the arc of a circle concentric with the pivotal center of the turn-spout O, so that the lower end of said turn-spout, which rests upon the said platform P' , may be moved so as to come opposite the end of either of said spouts. The top of the turn-spout O is connected to a receiving-hopper, o, attached to the bridge-trees D^2 , and the top of the belt-pulley and the said hopper is covered by a hood, o'. These parts are arranged in a well-known manner, and form no part of my invention.

In order to provide a simple and easily-constructed connection between the turn-spout O and hopper o which will not readily get out of order or become choked with grain, I provide a depending flange, o^2 , Fig. 6, upon the hopper o, and make the upper end of the turn-spout O of sufficient internal diameter to fit over it and be readily rotated thereon. The weight of the turn-spout is supported and it is kept in place by a collar, o^3 , placed upon the vertical rod O', by which the turn-spout is operated, which collar o^3 is placed above the bearing of the said rod in the frame D^4 .

I preferably make the working-floor E independent of the frame of the building, and support it on posts e e from the ground, and independently of the foundation of the building. This mode of construction is for the purpose of preventing any settlement in such floor,

which, as before stated, is liable to occur to the main structure on account of the weight of the grain stored therein. Such settlement of the working-floor would be objectionable, because the grain-cleaner L, which rests on said floor, would be thereby changed in position with reference to the driving-shaft d^6 , and the driving-connections between them thrown out of line. The weighing-hopper N also rests upon the floor E, and any settlement or tilting of the said floor would render the action of the weighing apparatus inaccurate, and on this account also such settlement would be objectionable.

In the floor of the driveway is a rectangular opening, f, through which grain from a wagon may be dumped into the bins G and G'. The opening f is provided with a trap-door, f', which is closed for the passage of horses over it, and is opened when the wagon is in position to be dumped. Pivoted timbers Q Q are placed in the floor, on either side of the opening f, which are adapted to receive the wheels of a wagon, and to be tilted with such wagon, so as to discharge its contents into the opening f in a well-known manner.

At the edge of the floor, across the ends of the openings in which the beams Q are pivoted, I place two iron rollers, q q, Fig. 5, which are so situated that the rear wheels of a wagon placed on said timbers will strike them when the timbers are tilted. The distance through which the timbers Q are tilted is limited, the ends being ordinarily thrown down about two feet, and no special locking device is necessary to retain the wagon upon the timbers, because the wheels come in contact with the edge of the floor and prevent the wagon from moving. The object of the rollers q is to protect the edge of the floor from being scraped and worn away by the wheels, and to allow the wheels to move down while resting against such rollers without friction.

The opening f, through which the grain is dumped into the receiving-bin G, is arranged centrally over the partition G^2 , between said bins. In order that the grain may be dumped into one or the other of the bins G, as desired, I have provided a swinging guide-board, f^2 , which is pivoted to the top edge of the partition G^2 , beneath the opening f, and its upper and free end is adapted to be swung from one side of said opening to the other, so as to deflect the grain thrown into said opening to one side of the partition or the other, for the purpose above stated.

It is found, in many instances, where a sliding gate is used at the bottom of a deep bin, that the pressure of the grain upon the upper surface of such gate is liable to render it difficult to be moved. To avoid this difficulty I have provided a stationary support over or in front of a sliding gate, which support is adapted to take the direct pressure of the grain from said gate, but allows the grain to pass around its edges to the gate when the latter is opened. Such a support is shown in

connection with the gate in Fig. 2, in the bottom of the bin M over the weighing-hopper. The gate mentioned is operated by a lever, m^1 , and is arranged to slide horizontally, and over it I have placed a stationary support, m^2 , which has a double-inclined top, as shown, but may be a flat board, or in other desirable shape.

In order to provide a weighing-hopper the scale-beam of which will be convenient to the operator of the elevator on the working-floor, and which is in proper position to receive the grain from the bin M and to discharge it at a proper height outside of the building, I support the weighing-hopper N upon vertical standards $n\ n$, secured on a scale-platform, N', which rests upon the working-floor. The side n' of the weighing-hopper, which is adjacent to the wall of the building, is preferably made vertical, as shown, in order to economize space in the building.

I claim as my invention—

1. In a building for storing grain, the combination, with means for elevating the grain, of a series of bins having a substantially unitary hopper-bottom common to all the bins of the series and sloping toward a central pit, in which the lower end of the elevating device is placed, substantially as described, and for the purpose set forth.

2. In a building for storing grain, the combination, with means for elevating the grain, of a unitary hopper-structure forming the bottoms of a series of bins, and radial partitions between said bins, whereby the grain may be discharged at a central point to the elevating device, substantially as described.

3. In the elevator-structure described, the combination of two elevating devices, two or more storage-bins, C, constructed to discharge to the several elevating devices, and a bin, I, arranged to discharge to either of the said elevating devices, substantially as and for the purpose set forth.

4. In a building for storing grain, the combination of two elevator-belts, receiving-bins G, and storage-bins C, arranged to discharge to the said elevator-belts, a cleaner, a bin, I, constructed to discharge to either elevator-belt, and means for conveying the grain from the top of each elevator-belt to the cleaner and

bin I, and means for conveying the grain from the top of the elevator-belts to the storage-bins, or outside of the building, substantially as described.

5. The combination, with the elevator-belts D and storage-bins C, of bins K, arranged to discharge into a grain-cleaner, bins M, arranged to discharge into a weighing-hopper, and means for conveying the grain from the top of each elevator-belt to the said bins C, K, and M, substantially as and for the purposes set forth.

6. In a building for storing grain, an elevator having its casings or legs constructed to form the supporting-frame upon which the several operative parts are mounted, substantially as described.

7. The combination, with the floor of the driveway F, having an aperture, f, of means for directing grain discharged through said aperture into either of the bins G, as desired.

8. The combination, with the floor F, having an aperture, f, and the partition G', of the pivoted board f', substantially as and for the purpose set forth.

9. In a device for dumping grain, the combination, with a floor, F, of a roller, g, located and operating substantially as described, and for the purpose set forth.

10. The combination, with the floor F and the dumping-timbers Q, of rollers g, having bearings in the said floor at the end of the dumping-timbers, substantially as described, and for the purpose set forth.

11. In a structure for elevating and storing grain, a working-floor, E, supported from the ground, independently of the other parts of the building, substantially as described.

12. The combination, with the floor E and the bin M, of a weighing-hopper, N, placed above a scale-platform resting on said floor, and supported by standards n therefrom, substantially as and for the purposes set forth.

In testimony that I claim the foregoing as my invention I affix my signature in presence of two witnesses.

MARQUIS F. SEELEY.
